UNITED STATES PATENT OFFICE.

AXEL ERIK HAGBERG AND JOHAN ERIK PERSSON, OF MILWAUKEE, WISCONSIN.

INTERNAL-COMBUSTION MOTOR.

Application filed November 9, 1922. Serial No. 599,911.

To all whom it may concern:

Be it known that we, AXEL ERIK HAGBERG and JOHAN E. PERSSON, both subjects of the King of Sweden, and residents of Milwaukee, in the county of Milwaukee and State of Wisconsin, have invented new and useful Improvements in Internal-Combustion Motors, of which the following is a full, clear, and exact description.

10 This invention relates to internal combustion motors.

The general object of this invention is the provision of a simple and efficient internal combustion motor provided with means for 15 utilizing power created by the exploding of explosive mixtures without using cylinders, pistons and cranks.

This object is accomplished by providing a casing in which a plurality of explosion 20 chambers are formed, locating in the explosion chambers means for compressing the explosive charges, associating with the casing a turbine wheel which is fixed to a shaft rotatably mounted in the casing, forming in 25 the end of the casing passages which convey the products of combustion from the explosion chambers to the turbine wheel, mounting on the casing means for controlling the flow of the products of combustion through 30 the passages, and providing means driven from the turbine wheel shaft for operating the means for controlling the flow of the products of combustion and the means for compressing the explosive charges.

35 This and other objects of the invention will be more clearly understood from the following detailed description and accompanying drawings.

Figure 1 is a longitudinal section along 40 the line 1-1 of Figure 2, showing the construction of the motor:

Figure 2 is a vertical cross section along the line 2-2, Figure 1;

Figure 3 is a cross section along the line 45 3-3, Figure 1;

Figure 4 is a vertical cross section along the line 4-4, Figure 1;

Figure 5 is a vertical cross section along the line 5-5, Figure 1;

50 Figure 6 is a horizontal section along the line 6-6, Figure 1;

Figure 7 is a horizontal section along the line 6-6, Figure 1, showing the plate which serves to control the flow of the products of 55 combustion against the turbine wheel shaft-

ed to a position between the openings in the casing wall.

Referring to the above-mentioned figures, the invention includes a cylindrical casing 10 provided with a plurality of walls 11 extending radially inward. Formed in opposite ends of the cylindrical casing are openings 12 and 13. Encircling the opening 13 and extending parallel to the cylindrical casing is a rim 14 provided with an external 60 thread at its outer end. Rotatably mounted on the rim 14 and abutting against the end of the cylindrical casing 10 is an annular plate 15 having attached to its lower edge a yoke 16 in the ends of which two pulleys 17 and 18 are rotatably mounted. A hollow annular block 19 having an annular slot 20 cut in its inner face is mounted on the rim 14, the rim fitting into the annular slot and its external thread engaging with a thread provided on the metal defining the outer edge of the annular slot 20. Attached to the annular block 19 by means of screw bolts 28 is a turbine casing 24. A shaft 29 having one end rotatably mounted in the frame 30 extends through the casing 10, the annular block 19 in which it is journaled, and into the turbine casing 24. Fixed to the end of the shaft 29 by means of the key 26 is a turbine wheel 25. A collar 27 is also mounted 75 on the end of the shaft 29 to retain the turbine wheel in position. A plurality of openings 22 are formed in one end of the cylindrical casing 10, one opening being located 80 on each side of each wall 11. These openings are adjacent to the walls 11 and to the outer wall of the casing 10. A plurality of openings 23 are formed in the plate 15. The number of these openings 23 will be determined by the number of openings 22 in the 85 end of the cylindrical casing 10. In this case the number of openings 23 is equal to one-half the number of the openings 22 in the end of the casing. The openings 23 are evenly spaced about the plate 15 and when 90 the plate stands in its central position each opening 23 is located midway between a pair of openings 22 formed in the end of the casing 10, as shown in Figure 7. Passages 21 are provided in the outer rim of the hollow annular block 19 in alignment with the openings 22 in the end of the casing. These 95 passages are shaped like a nozzle and are located in alignment with the blades of the turbine wheel 25.

Extending through the outer wall of the casing 10 are a plurality of openings 33, one of which is located on each side of each wall 11 thus positioning two openings 33 between any two of the walls 11. One-way valves 34 are mounted in the openings 33 for controlling the flow of an explosive mixture through the openings. Pipe lines 35 leading from carburetors 36 communicate 10 with each of the openings 33 for conveying the explosive mixture to the casing 10. A plurality of spark plugs 37 are mounted in the ends of the casing for firing the explosive mixture conveyed into the casing by 15 means of the pipes 35. A spark plug is provided for each opening 33.

Rotatably mounted on the shaft 29 is a rotor including a cylindrical member 31 and a plurality of walls 32 extending radially outward. The number of walls 32 provided is equal in number to the number of walls 11 carried by the casing 10. A rotor wall 32 is located in each space between the walls 11 of the casing. A yoke 38, the arms of 25 which carry two wheels 39 and 40, is formed integral with the cylindrical member 31. The cylindrical member 31 in conjunction with the casing 10 and the casing walls 11 forms a plurality of combustion chambers 30 41.

A shaft 42 is rotatably mounted in the frame 30 and the cylindrical casing 10. Fixed to the inner end of the shaft 42 is a cam 43 mounted in alinement with the 35 yoke 38 and between the wheels 39 and 40 carried by the arms of the yoke. Two other gears 44 and 45 are fixed to the shaft 42, the gear 44 meshing with a pinion 46 fixed to the shaft 29. A shaft 47 rotatably 40 mounted in the frame 30 carries a gear 48 meshing with the gear 45. Fixed to the shaft 47 is a cam 49 located between the arms of the yoke 15. A squared end 50 is formed on the end of the shaft 47 so that 45 the shaft may be engaged by a crank or other means for rotating it.

The operation of this internal combustion motor is as follows:

By means of a crank or other device attached to the squared end of the shaft 47 the latter is rotated. A cam 49 fixed to the shaft 47 rocks or oscillates the plate 15. The rotor is oscillated or rocked about the shaft 29 by the cam 43 which is operated from the shaft 47 through gears 48 and 45 and the shaft 42. Considering Figure 2, when the motor is set in operation by rotating the shaft 47 the openings 22 in the end of the casing are all closed by the plate 15. The rotor operated through the cam 43 begins to move counter-clockwise, compressing the air located in the front of the wings 32 and reducing the atmospheric pressure behind the wings 32 in the chambers 65 41. When the atmospheric pressure in the

chambers 41 has been reduced explosive charges are fed into the combustion chambers 41 through the pipe lines 35 and the one-way valves 34. After the rotor has completed its counterclockwise movement it 70 comes to a standstill and for a moment is in a stationary position. The plate 15 is shifted and the openings 23 are alined with the openings 22 in the end of the casing adjacent and in a clockwise direction from the 75 walls 11. The compressed air in front of the rotor walls 32 escapes into the turbine casing 24 and impinges on the blades of the turbine wheel 25 rotating the shaft 47. At the same instant as the rotor begins its 80 clockwise movement the plate 15 shifts, closing the openings 22 adjacent the walls 11 and in a clockwise direction from them. As the rotor moves clockwise, the charges located in the combustion chambers in front 85 of the rotor walls 32 are compressed and fresh charges are fed into the combustion chambers 41 in the rear of the rotor walls 32. When the rotor has completed its clockwise movement and for a moment is 90 in a stationary or what we term the "dwell" position, the compressed charges are fired. At the same instant as the firing of the charges the plate 15 shifts, alining the openings 23 in the plate 15 with the openings 22 95 adjacent the walls 11 and in a counterclockwise direction from them. This allows the gases generated by the firing of the charges to escape into the turbine casing 24 to impinge on the blades of the turbine wheel 25, 100 operating the latter. Now the turbine wheel by means of the shaft 29, pinion 46, gear 44 and the cam 43 operates the rotor, rocking it counterclockwise. At the same instant as the rotor begins its counterclockwise movement the plate 15 shifts, closing the openings 22 adjacent the walls 11 and in a counterclockwise direction from them. As the rotor moves counterclockwise the 105 charges located in the combustion chambers 110 in front of the rotor walls 32 are compressed and fresh charges are fed into the combustion chambers 41 in the rear of the rotor walls 32. When the rotor has completed its counterclockwise movement and for a 115 moment is in a stationary or dwell position the second compressed charges are fired. At the same instant as the firing of the charges the plate 15 shifts, alining the openings 23 in the plate 15 with the openings 22 120 adjacent the walls 11 and in a clockwise direction from them. This allows the gases generated by the firing of the charges to escape into the turbine casing 24 to impinge on the blades of the turbine wheel 25.

A series of operations similar to the ones described above continue. First, the rotor is operated through the cam 43 and compresses the charges located in front of it as it moves and reducing the pressure behind it 130

to allow new charges to be fed into the combustion chambers. The rotor is now in a stationary or dwell position, the compressed charges are fired and the cam 49 operates 5 the plate 15 to open the passages in front of the walls 32 into the turbine chamber, allowing the gases generated by the firing of the charges to operate the turbine. The rotor changes its direction, the plate 15 10 shifts, closing the passages into the turbine chamber. The rotor as it now moves compresses the charges located in front of it and reduces the pressure behind it to allow new charges to be fed into the combustion chambers. Again the rotor is in a stationary or 15 dwell position, the compressed charges are fired, the plate 15 opens the passages in front of the walls 32 into the turbine chamber, allowing the gases generated by the firing 20 of the charges to operate the turbine. Again the rotor changes its direction. This continuous series of operations operates the turbine wheel and the shaft 29 from which power may be transmitted by any transmission system.

We would state in conclusion that while the illustrated example constitutes a practical embodiment of our invention we do not limit ourselves strictly to the exact details 30 herein illustrated since manifestly the same can be considerably varied without departing from the spirit of the invention as defined in the appended claims.

Claims:

35 1. An internal combustion motor of the character described comprising a main casing, having a plurality of walls spaced about the same and extending inward, said casing having a plurality of passages leading through one end, a passage being located on each side of each wall, a turbine casing 40 mounted on said main casing, a turbine wheel fixed to a shaft rotatably mounted in the main casing, the blades of said turbine wheel being located in alignment with the passages leading from the main casing, a rotor having a plurality of walls extending outward rotatably mounted on the shaft 45 extending through the main casing, said rotor serving in conjunction with the casing walls to form a plurality of combustion chambers, means for admitting an explosive charge to each combustion chamber, means driven from the turbine shaft to oscillate the 50 rotor to utilize the rotor walls for compressing the explosive charge, spark plugs located in each explosive chamber for firing the charge, and means operated from the turbine shaft for controlling the flow of the 55 products of combustion from the explosion chambers to the turbine wheel, said means comprising an oscillating plate, a pair of arms projecting therefrom, and a cam lying between said arms.

2. An internal combustion motor of the 65 character described, comprising a main casing having a plurality of walls extending inward, a shaft rotatably mounted in said main casing, a rotor having a plurality of walls extending outward loosely mounted on the 70 shaft so that it may be oscillated, said rotor serving in conjunction with the walls of the main casing to form a plurality of combustion chambers, a turbine wheel mounted on the main shaft external to the casing, means 75 for admitting explosive charges to the explosion chambers, means operated from the main shaft for oscillating the rotor to compress the explosive charges, spark plugs mounted in the main casing for igniting the 80 explosive charges, said main casing being provided with a plurality of passages for conveying the products of combustion to the turbine wheel, and means operated from the main shaft for controlling the flow of the 85 products of combustion through said passages, said means comprising an oscillating plate.

3. In an internal combustion motor of the class described including a main casing in 90 which a plurality of combustion chambers are formed, said casing having a plurality of passages leading through one end, and a turbine wheel rotatably mounted in alignment with said passages, a device for controlling the flow of the products of combustion from the combustion chambers to the turbine wheel comprising a plate mounted in conjunction with the main casing so that it may be oscillated, and means driven from 100 the turbine wheel for oscillating said plate to control the flow of the products of combustion from the combustion chambers to the turbine wheel, said means comprising a shaft and a cam carried thereby.

4. In an internal combustion motor of the character described, a casing, a rotor, means providing a plurality of combustion chambers, a turbine wheel and means for conveying the products of combustion from the 110 combustion chambers to the turbine wheel to operate the latter, means for controlling the flow of the products of combustion to the turbine wheel, means for oscillating the rotor, means carried by the rotor for compressing the charges and for drawing the charges into the combustion chambers when the rotor is operated, and means for driving the means for controlling the flow of the products of combustion to the turbine wheel 115 and means for oscillating the rotor driven from the turbine wheel, said last-mentioned means comprising a countershaft, a cam carried thereby, and means carried by said rotor for engagement with said cam.
